HEATER

Walter W. Owens, Glendale, Calif., assignor to
Owens Smokeless Orchard Heater, Incorporated,
Hollywood, Calif., a corporation of California

Application June 30, 1937, Serial No. 151,265

6 Claims. (Cl. 126—59.5)

This invention relates to heaters and pertains more particularly to that type used in orchards for dispelling frost or sudden cold, which latter has proven extremely detrimental to the proper growing of plants and fruit bearing trees.

Heretofore, as is well known in the art of plant husbandry, it has been customary to employ burners known as smudge pots. As presently constructed these smudge pots are provided with restricted draft producing passages so that the customary fuel, such as crude oil, waste crank case oil, old rubber, brickettes, etc., will smolder, thus creating a pall of heavy smoke with a minimum amount of heat in order to counteract the detrimental effect of frost or cold upon plants or fruit bearing trees. The use of these so called smudge pots has to some extent been effective in dissipating frost. However, such heaters have resulted in incalculable damage to surrounding property and more particularly to buildings and their contents, by depositing heavy coatings of soot or other foreign substances thereon.

The primary important object of this invention is to eliminate the foregoing objectionable features of the present type of burner by providing a device of the above character which has a greater heat producing capacity without the production of smoke, thus resulting in a clean and positive protection to the plants or trees by eliminating soot or the like and increasing the temperature of the surrounding atmosphere during sudden drops in temperature due to frost or cold.

Another important object of this invention is to provide a heater of the above character which is so constructed that a direct or positive draft may be initially produced for starting the burning of the fuel and which may then be converted into an indirect draft, thus resulting in a slow, economical consumption of the fuel and deflection of the resultant heat over a considerable area surrounding the heater.

A further important object of this invention is to provide a heater of the above character wherein incoming air to be heated is drawn into the fire pot from over the surrounding heater supporting surface and then deflected downwardly and outwardly from said heater in a substantially horizontal plane for a considerable distance over the stratum of incoming cold air, thus pre-heating the latter to some degree.

A still further object of this invention is to provide a heater of the above character from which the heat generated therein is distributed over a considerable surrounding area by deflection as contra-distinguished from reflection or radiation,

These and other important objects and advantages of the present invention will appear throughout the course of the following description and accompanying drawing, in which

Fig. 1 is a front elevation of the heater with the cover in open position.

Fig. 2 is a vertical sectional view taken on line 2—2 of Fig. 1 with the cover in closed position.

Fig. 3 is a bottom plan view of the heater, and

Fig. 4 is a top plan view of the cover with a movable damper therein.

Referring in detail to the drawing, A designates generally a pair of spaced metal supports, each having flat horizontal bottom portions 5, vertically extending ends 6 and flat horizontally extending and aligned top portions 7 formed to provide substantially elongated looped ground engaging runners.

Rigidly mounted upon the tops 7 of the runners by brackets 8, or by welding or other suitable means, is a metal frustro-conical heat deflecting shell 9 provided with an internal covering or lining 10, as shown in dotted lines Fig. 2 of asbestos or other suitable heat insulating material. However, the lining 10 may be dispensed with, dependent upon the gauge or thickness of the metal from which the heat deflecting shell is formed in the event that radiation of the heat through the shell 9 is also desired.

Partly telescoped within the heat deflecting shell 9, and suspended therein by means of brackets 11 and 12, in circumferentially spaced relation thereto is a fire pot 13. The upper and lower ends of the fire pot terminate below the upper and lower ends of the heat deflecting shell 35 respectively, while the lower end of the fire pot is further spaced relative to the ground or other heater supporting surface. The fire pot is provided adjacent its lower end with a slot or other suitably formed opening 14.

Secured within the lower end of the fire pot in a plane with the bottom wall of the opening 14, is a diametrically extending bar 15. Also secured within the firebox at a point diametrically opposite to the opening 14 is a supporting bracket 16, having its upper surface aligned with the bottom wall of said opening. Movable mounted upon the bar 15 as by means of rivet 17 and supported adjacent its peripheral edge by the bracket 16 is a perforated grate 18 having a part 19 extending through the opening 14 to provide an operating handle. Slidably mounted within the fire pot 13 and supported upon the grate 18 is a detachable fire pot lining 19.

A conically shaped cover 20 provided with a

handle 21 is removably secured to the upper end of the shell 9 by flexible connections 22 or other suitable means. The central portion of the cover is provided with a series of spaced draft openings 23 therethrough. Rotatably secured to the apex of the cover, by means of rivet 24, is a damper or valve member 25 which is also provided with a series of spaced openings 26 corresponding to the openings 23 formed in the cover proper. The 10 valve member 25 is provided with a handle 27 by which same may be readily rotated to move the openings 26 into or out of alinement with the openings 23 whereby to control the amount of direct draft through the firepot when the fire is 15 initially started.

In the operation of my improved heater, the cover 20 is swung to its open position and packaged fuel of a smokeless character is placed in the firepot 13 and supported by grate 18. The 20 cover is then closed and the valve member 25 rotated until the openings 26 therein aline or register with the openings 23 in the cover 20.

When the fuel is ignited, a direct draft is then 25 created through the firepot 13 and openings 23 and 26 of the cover and valve respectively. After the fire has burned sufficiently to generate a considerable amount of heat, the valve 25 is rotated to move the openings 23 and 26 out of register. Subsequently the draft and heat will be caused 30 to follow a path upwardly through the fire pot and thence downwardly and outwardly between the fire pot 13 and deflecting shell 9, thereby distributing the generated heat in a substantially horizontal direction over the cold air flowing into 35 the bottom of the fire pot and over a considerable area surrounding the heater. The ground engaging supports or runners will readily admit of the heater being transported from place to place without disturbing the fire.

40 It will be apparent that while I have shown and described the heater in preferred form, changes and modifications may be made in the structure disclosed without departing from the spirit of the invention as defined in the following 45 claims.

What I claim is:

1. In a heater of the character described, a pair of independent spaced elements for engaging the ground or other suitable supporting surface, the ground or other suitable supporting surface, 50 a substantially frusto-conical heat deflecting shell supported by and connecting said elements, a fire pot supported within said shell in circumferentially spaced relation thereto and terminating below said shell and above said supporting 55 surface, a cover for said shell, and a valve in said cover.

2. In a heater of the character described, a plurality of supports for engaging the ground or other suitable supporting surface, an open top 60 heat deflecting shell carried by said supports above said supporting surface a fire pot supported within said shell and spaced from the latter and from said supporting surface, a cover for said shell, and a damper carried by said cover.

65 3. In a heater of the character described, a pair of spaced independent ground engaging

looped runners of elongate form, a flared heat deflecting shell secured to and supported by said runners in spaced relation to the ground, and a firepot supported within and circumferentially spaced from said shell, said firepot having its top and bottom edges terminating below the top and bottom of said shell, respectively, and having its bottom edge supported above and spaced from the ground. 5

4. An orchard heater, including a shell having an open bottom and a closed top, a fire pot within the shell having an open top and an open bottom, means to connect the pot to the shell to provide free space between the sides of the pot and the sides of the shell, and to also provide 10 free space between the top of the pot and the top of the shell, the bottom portion of the pot projecting downwardly below the bottom of the shell, and means to support the heater with the open bottom of said shell and with the open 15 bottom of the pot spaced above the surface of the ground, whereby heat generated in the pot will flow upwardly and be deflected downwardly by the closed top of the shell through the said 20 space between the sides of the shell and pot, and thence deflected by the lower projecting end of the pot in a downward and outward direction through the open bottom of the shell. 25

5. An orchard heater, including a shell having an open bottom and a closed top, a fire pot within the shell having an open top, means to connect the pot to the shell to provide free space between the sides of the pot and the sides of the shell, and to also provide free space between the top of the 30 pot and the top of the shell, and means to support the heater with the bottom of said shell spaced above the surface of the ground, the bottom of the pot being open whereby to freely receive the surrounding air through the space between the bottom thereof and the ground on 35 which the heater is supported, whereby heat generated in the pot will flow upwardly therethrough, and be deflected downwardly by the closed top of the shell through the space between the sides of the shell and pot and will then flow 40 outwardly from the lower end of the shell and beyond the sides of the shell. 45

6. In a heater of the character described, a substantially frusto-conical shell for deflecting products of combustion, a fire pot, means supporting said fire pot within said shell in circumferentially spaced relation thereto to provide a downward passage for products of combustion, said fire pot having an open top spaced below the upper edge of said shell and communicating with 50 said circumferential space and an open lower end terminating below the lower edge of said shell, means for supporting said shell and fire pot relative to the ground or other supporting surface, to provide for the ingress of air into the fire pot 55 and the egress of the products of combustion downwardly through the circumferential space between the shell and fire pot, a cover for the upper end of said shell, and draft control means carried by said cover. 60
